DESIGN.

R. J. CHAPMAN.

WALL ORNAMENTATION.

No. 15,516.

Patented Nov. 4, 1884.

UNITED STATES PATENT OFFICE,

ROBERT J. CHAPMAN, OF PHILADELPHIA, PENNSYLVANIA.

DESIGN FOR WALL ORNAMENTATION.

SPECIFICATION forming part of Design No. 15,516, dated November 4, 1884.

Application filed August 1, 1884. Term of patent 3½ years.

To all whom it may concern:

Be it known that I, ROBERT JONES CHAPMAN, a citizen of the United States, residing at Philadelphia, and State of Pennsylvania, 5 have invented and produced a new and original Design for Wall Surface Ornamentation, of which the following is a specification, reference being had to the accompanying drawing, forming part thereof.

10 The figure is a view of a surface ornamented with my design.

The design consists of a series of curved ridges upon a flat surface, the spaces between the ridges tapering from the center to each 15 end, which produces the appearance of a sur-

face in high relief, according to the direction of the light. These raised lines are all alike in any series—as, for instance, all those within the letters *a b c d*—and the ornamentation shows a number of these series, K H. 20

I claim—

The design for wall ornamentation, consisting of a series of ridges in curved lines, with the spaces between tapering from the center to both ends, having the appearance of a surface in relief, as herein shown and described. 25

ROBT. J. CHAPMAN.
